UNITED STATES PATENT OFFICE.

ALFRED N. BESSESEN, OF MINNEAPOLIS, MINNESOTA.

SYRINGE.

Application filed August 6, 1923. Serial No. 656,087.

To all whom it may concern:

Be it known that I, ALFRED N. BESSESEN, a citizen of the United States of America, residing at Minneapolis, in the county of 5 Hennepin and State of Minnesota, have invented certain new and useful Improvements in Syringes, of which the following is a specification.

This invention relates to new and useful 10 improvements in syringes best adapted for use to produce local anesthesia.

An important object of the invention is to provide a syringe of the above mentioned type which is operated by air or gas pressure.

A further object of the invention is to provide a syringe that is suitably constructed for permitting a high pressure to be maintained therein over a considerable 20 period of time.

A further object of the invention is to provide a local anesthesia syringe which may be used for infiltration, under known pressure, of body tissues for surgical purposes.

A further object of the invention is to provide a syringe which requires very little effort to operate.

A still further object of the invention is 30 to provide a device of the above mentioned type which may be used quickly, promptly, and safely for producing local anesthesia.

Other objects and advantages of the invention will be apparent during the course 35 of the following description.

In the accompanying drawing forming a part of this specification and in which like numerals are employed to designate like parts throughout the same,

40 Figure 1 is a longitudinal sectional view, partly in elevation, of the syringe embodying this invention,

Figure 2 is a fragmentary sectional view of a portion of the needle carrying end of 45 the syringe shown in Fig. 1, and

Figure 3 is a longitudinal sectional view of the needle employed.

In the drawing, wherein for the purpose 50 of illustration is shown a preferred embodiment of this invention, the numeral 5 designates the rear end section of the barrel or body portion of the syringe. This section 5 is externally screw threaded at its inner end for threadedly engaging the cap 6 which carries a nipple 7 having the pressure gage 8 suitably carried thereby and a

hose connection 9 having a check valve 10 located therein for allowing the entrance of a suitable fluid under pressure into the barrel or body portion of the device. The 60 opposite end of the barrel section 5 is externally screw threaded for detachably being connected to the enlarged collar portion 11 of the outer end section 12 of the barrel or body. This threaded end of the body or barrel section 5 is provided with a tapered edge 13 that is adapted to seat against a similarly shaped surface formed in the enlarged collar 11 of the barrel section 12. The outer end of this barrel section 12 is externally screw threaded for engaging the cap 14 which is provided with an arcuately formed nozzle portion 15. The said cap 14 and nozzle portion 15 are provided with a 70 passage 16 having a tapered valve seat 17 formed at its inner end that is adapted for being engaged by the conically-shaped valve element 18 which is controlled by the push button 19 having a coil spring 20 for normally retaining it in its inoperative position and for retaining the valve element 18 against the seat 17. This push button 19 is provided with a shank portion 21 having a cone-shaped valve surface 22 that is adapted 75 for seating against the valve seat 17 which is formed in the outer end of the valve rod opening 24. The extreme outer end of the nozzle portion 15 is externally screw threaded for detachably receiving the needle clamping collar 25 which carries the needle 26 and is adapted for alining the bore 27 of the needle with the passage 16 formed in the cap 14 and nozzle 15.

It will be noticed by inspecting Fig. 1, 80 that both of the barrel sections 5 and 12 have bores of equal diameter for the purpose of accomodating the pressure operated piston 28 which is provided with a stem portion 29 having at its outer end a handle portion 30.

The operation of the syringe embodying 85 this invention is as follows:—

The barrel or body section 5 is detached 90 from the section 12 and the pressure operated piston 28 is removed from the latter section by grasping the handle portion 30. The barrel section 12 is then filled with a suitable anesthesia producing drug. The pressure operated piston 28 is then placed 95 within the barrel section 5 and the two sections are threadedly connected. It is to be understood that the connection 9 carried by

the cap 6 is connected to a suitable source of supply, such as a gas or air pressure pump. This gas or air pressure may then be operated for producing a desired pressure within the entire barrel section of the syringe, the said pressure therewith being recorded upon the gage 8. It will be seen that the valve element 18 will prevent the outward passage of the drug 31 which is positioned within the barrel section 12. When a surgeon, or other suitable person, desires to infiltrate certain body tissues for producing local anesthesia, it is merely necessary for him to properly insert the needle 26 into the tissues and press the button 19 for unseating the valve element 18. The pressure within the barrel section of the syringe will cause the piston 28 to move longitudinally thereof for forcing the drug 31 through the passage 16 and through the bore 27 of the needle. The valve 22 will engage the valve seat 23 when the button 19 is pressed inwardly and will thereby prevent the escapement of the anesthesia producing drug through the valve stem opening 24. It is very apparent that the construction of this syringe allows for the maintaining of a very high pressure within the same and that this pressure may be maintained for any desired length of time. The operation of the valve element 18 for allowing the drug 31 to be infiltrated into the body tissues will not require any great effort upon the part of the operator and will therefore eliminate any danger of breaking the needle 26 which very frequently happens when manually operated syringes are employed.

It is to be understood that the form of this invention herewith shown and described is to be taken as the preferred example of the same, and that various changes in the shape, size, and arrangement of parts may be resorted to without departing from the spirit of the invention or the scope of the subjoined claims.

Having thus described the invention, I claim:—

1. In a syringe, a barrel portion, a removable cap carried by said barrel portion, said cap having a passage therethrough, a conical valve seat formed in said cap at one end of said passage, said cap having an

opening extending therethrough from the valve seat, a second valve seat formed in said cap at the outer end of said opening, a rod movably positioned in said opening, a valve element carried by each end of said rod adapted to engage said valve seats one at a time, means associated with said rod for normally retaining one of said valves in engagement with the first mentioned valve seat for closing said passage, and means carried by said rod for unseating this last mentioned valve and for seating the other valve.

2. In a syringe, a barrel portion, a cap removably carried thereby, said cap having an opening therethrough, a conical valve seat formed at each end of said opening, said cap having a passage extending therethrough and opening into the wall of the valve seat at the inner end of said opening, a rod slidably positioned within said opening and having a length greater than that of the opening, a valve element carried by each end of said rod, means for normally retaining the valve element at the inner end of said rod seated for closing said passage, means for manually unseating the valve element at the inner end of said rod and seating the valve element at the outer end of said rod, and a hypodermic needle removably carried by said cap in communication with the outer end of said passage.

3. In a syringe, a barrel portion, a removable cap carried thereby, said cap having an opening therethrough, a conical valve seat formed at each end of said opening, said cap having a passage extending therethrough and opening into the wall of the valve seat at the inner end of said opening, a rod slidably positioned within said opening and having a length greater than that of the opening, a valve element carried by each end of said rod, resilient means for normally retaining the valve element at the inner end of said rod seated for closing said passage, and a push button connected to said rod for manually unseating the valve element at the inner end of said rod and seating the valve element at the outer end of said rod.

In testimony whereof I affix my signature.

ALFRED N. BESSESEN
